(57) **CLAIM**
I claim the ornamental design for a tapered tail rollable sledge and slide, as shown and described.

DESCRIPTION

FIG. 1 Is a top plan view of a tapered tail rollable sledge and slide, showing my new design, when the article is configured ready for use,

FIG. 2 Is a top front perspective view thereof,

FIG. 3 Is a left hand perspective view thereof, with the article configured and arranged as would be required to form an anchorable Slide on sand. The right hand elevation is a mirror image of the left hand elevation,

FIG. 4 is a top front perspective view of the article when in a rolled configuration and stood on its side.

FIG. 5 Is a top perspective view of the article prepared in a rolled configuration and stood on its side,

FIG. 6 Is a top plan view of the article when in a fully unrolled, flat configuration. The bottom plan view of the article when configured thus, is a mirror image,

FIG. 7 Is a side perspective view of the article when in a fully rolled configuration and secured with one tab located in one slot; and,

FIG. 8 Is a bottom plan of the article.

In FIG. 4 the broken line rope in the drawings is unclaimed subject matter only and forms no part of the claimed design.
